INDOLE RECOVERY PROCESS

John R. Anderson, Pittsburgh, Pa., and David W. Peck, South Charleston, W. Va., assignors to Union Carbide Corporation, a corporation of New York

Application May 9, 1955, Serial No. 507,112

9 Claims. (Cl. 260—319)

This invention relates to a continuous extraction process whereby a mixture of indoles and hydrocarbons is separated into one or more fractions containing the bulk of the hydrocarbons and a fraction containing the bulk of the indoles. More particularly the invention relates to the application of this method to the industrial products in which indoles occur, such as the neutral light oil from coal hydrogenation.

Indole is used in the production of perfumes and in the synthesis of tryptophane, an essential amino acid. More widespread industrial use would be likely except for its scarcity and high cost. It occurs naturally in organic sources such as oil of jasmine, clove oil and the products of putrefaction of amino acids. The major commercial source at present is the coke industry, where indole is recovered from coal tar oil. A new source of supply, however, is now being found with the commercial development of coal hydrogenation processes. Indole is found in the so-called neutral light oil fraction derived from the coal by hydrogenation. The neutral light oil fraction is composed principally of aromatic and paraffin hydrocarbons; the tar acids and bases having been separated from it. Although indole, which has the formula:

is a nitrogen containing compound similar in structure to the nitrogen base, it is neutral to weakly acid in nature and resembles the aromatic hydrocarbons in many of its properties, which accounts for its being found in the neutral light oil fraction rather than with the nitrogen bases as might be expected.

In the past indole has been recovered from the appropriate fraction of coal tar oil by taking advantage of the weakly acidic properties of its N—H group. This involves precipitating the potassium or sodium salt of indole, separating the salt from the oil mixture, and then hydrolyzing the salt to give indole and sodium or potassium hydroxide. A number of German patents, including Nos. 223,304, 238,138 and 454,696, disclose this method, which is unsatisfactory in that multiple treatment of the indole fraction is necessary to obtain indoles of sufficiently high quality, and each step must be carried out batchwise.

The present invention provides an improved continuous process whereby a mixture of indoles and aromatic hydrocarbons can be prepared, which mixture contains only a small proportion of aromatic hydrocarbons and is substantially free from aliphatic hydrocarbons and partially hydrogenated polynuclear compounds. Applied to the industrial products in which indoles occur, such as neutral light oil from coal hydrogenation, coke oven oil, or coal tar oil, or in fact to any hydrocarbon mixture containing indoles, the present invention yields an aromatic hydrocarbon fraction having a relatively high concentration of

2

indoles. This fraction may then be treated in any desired manner to recover the indoles. Prior art methods include precipitation of the sodium or potassium salts. Indoles may also be recovered from the indoles and aromatic hydrocarbons mixture produced by the invention by employing the azeotropic distillation process disclosed in U.S. patent application Serial No. 507,168, concurrently filed by James V. Murray, Jr., John D. Fales and Charles H. Young. Murray et al. teach that their azeotropic distillation is best applied to a mixture of indoles and aromatic hydrocarbons containing substantially no nonaromatic hydrocarbons or partially hydrogenated polynuclear compounds and this type of mixture is produced by the present invention.

According to the method of our invention, the neutral light oil or other mixture of indoles and hydrocarbons is first extracted with a 1,2-alkylene carbonate containing from three to four carbon atoms. Ethylene carbonate is preferred but propylene carbonate may also be used. The volume ratio of carbonate to indole-bearing oil may be from 1:20 to 20:1. Atmospheric pressure and a temperature up to about 10 degrees above the freezing point of ethylene carbonate, or room temperature in the case of propylene carbonate, are preferred, but temperatures up to the temperature where appreciable decomposition of the carbonate occurs are operable. The selectivity and capacity of the carbonate solvent may be adjusted, if desired, by the admixture with the carbonate of minor amounts of other substances, such as water. The extraction may be run as a single stage batch extraction but is preferably conducted as a multistage continuous extraction. Mechanical aids such as mixers, packing, baffles and the like may be contained in the extraction apparatus. This carbonate extraction removes as extract substantially all the indoles present, together with the more highly aromatic hydrocarbons, such as naphthalene. This extract represents a more concentrated indole mixture than the neutral light oil or other mixtures from which it was derived, and after removal of the carbonate, the indole could be removed directly by azeotropic distillation as disclosed in the Murray et al. application, or by other suitable means. There is still, however, a large proportion of aromatic hydrocarbons present in admixture with the indoles and the removal of the carbonate at this stage is difficult, particularly in view of the tendency of the carbonate to decompose and be degraded during the distillation which is customarily employed to remove or recover it.

We have discovered a method, however, whereby the indoles may be concentrated even further after their extraction with an alkylene carbonate, and whereby the carbonate may be recovered efficiently for recycle in the process. According to our invention the carbonate extract containing indoles and aromatic hydrocarbons is further extracted with a naphtha such as n-heptane, petroleum ether or cyclohexane which removes the bulk of the aromatic hydrocarbons and leaves as residue the carbonate, some residual aromatic hydrocarbons and most of the indoles, with less than five percent of the total indoles ordinarily being lost to the extract. The naphtha used for the extraction may be any low-boiling non-aromatic hydrocarbons, preferably those boiling between 50° and 110° C. The solvent to feed ratio for the extraction should be between 1:20 and 20:1, with about 2:1 being preferred. The pressure and temperature should be such that the feed, the solvent, the extract and the raffinate are all in the liquid state. Atmospheric pressure is ordinarily suitable, and room temperature is suitable if propylene carbonate is the alkylene carbonate used. If ethylene carbonate, which has a melting point of about 36° C. is used, the operating temperature must be above the melting point. Temperatures of from 36°

to 50° C. are preferred, although temperatures up to about 140° C., the temperature at which appreciable decomposition of ethylene carbonate occurs, may be used. The residue is then extracted with a low-boiling alkyl ether such as isopropyl ether or n-butyl ether which removes as extract the indoles and the residual aromatic hydrocarbons, as well as a small amount of the carbonate, and leaves the carbonate as residue which can be recycled. The solvent to feed ratio should be about 1:1. Pressure and temperature limitations are the same as those given immediately above for the naphtha extraction. The alkyl ether is then distilled from the extract leaving the indoles, the residual aromatic hydrocarbons and the small quantity of carbonate which had been dissolved by the isopropyl ether. A final extraction with water is then employed to remove residual carbonate and leave as product a mixture in aromatic hydrocarbons of a relatively high proportion of indoles. Indole-bearing oils also frequently contain phenolic compounds and nitrogen bases. Compounds of these types are not separated from the indoles by the process of the invention and must be removed by established techniques.

It is to be understood that in speaking of extracting indole-bearing oils with an alkylene carbonate in the present invention, we intend applying the process to all types of indole-bearing oils including those which contain little or no nonaromatic hydrocarbons. With these latter type of oils, the term extraction includes adding the carbonate to the oil to dissolve the indoles and aromatic hydrocarbons making up the oil. The carbonate will then serve as a solvent to hold the indoles while the aromatic hydrocarbons are extracted by the naphtha backwash.

The drawing is a flow sheet of the process of the invention. The mixture of indoles and hydrocarbons, such as neutral light oil, is introduced into an extractor 11 through line 12. The carbonate solvent is introduced into the extractor 11 through line 13. The extract from extractor 11, comprising the carbonate extraction solvent, the indoles and the aromatic hydrocarbons is led out through line 14 into a second extractor 15, while the residue of aliphatic and more hydrogenated aromatic hydrocarbons is removed from the extractor 11 through line 16. In the case of oils containing little or no nonaromatic hydrocarbons where the carbonate will be used primarily as a solvent rather than as an extracting agent and a solvent, the extractor 11 may be eliminated and the carbonate solvent in line 13 and the mixture of indoles and hydrocarbons in line 12 may be mixed directly and conducted through line 14 into the second extractor 15. Naphtha is introduced into the second extractor 15 through line 17. After the naphtha extraction, the extract, comprising naphtha and the bulk of the aromatic hydrocarbons is removed through line 18 while the residue, comprising carbonate, indoles and residual aromatic hydrocarbons is removed through line 19 and led into a third extractor 20.

A third solvent, isopropyl ether, is led into the third extractor 20 through line 21. After the ether extraction the extract, comprising isopropyl ether, indoles, residual aromatic hydrocarbons and remaining residual carbonate is led out of the third extractor 20 through line 22 and into a stripping still 23. The residue of carbonate solvent is removed from the third extractor 20 through line 24 and is recycled through line 24 back to the carbonate feed line 13 of the first extractor 11, for reuse in the process. The distillate from the stripping still 23, comprising isopropyl ether, is removed through line 25 and recycled through this line to the isopropyl ether feed line 21 of the third extractor 20, for reuse in the process.

The residue from the stripping still 23, comprising indoles, residual aromatic hydrocarbons and remaining residual carbonate, is removed through line 26 and led into a fourth extractor 27. Water as a solvent is introduced

into the fourth extractor 27 through line 28 to wash out residual carbonate. At this point, if necessary, any phenols or nitrogen bases present must be removed by conventional techniques such as washing with aqueous caustic to remove the phenols and with an aqueous mineral acid to remove the nitrogen bases. As these techniques will also remove or destroy any residual carbonate present, water washing to remove carbonate must be applied first if recovery of the residual carbonate is desired. The extract from the fourth extractor 27, comprising water and residual carbonate, is removed through line 29 and may then be conducted to a carbonate recovery apparatus for recovery of the carbonate for eventual recycle to the process. The residue from the fourth extractor 27 is removed through line 30 and comprises the final product of the process, a concentrated mixture of indoles in aromatic hydrocarbons.

To complete the continuous process, a second stripping still 31 is provided for separation of the naphtha and aromatic hydrocarbon mixture from the second extractor 15. The extract from the second extractor 15, which comprises naphtha and the bulk of the aromatic hydrocarbons from the original feed to the process, is removed from the extractor 15 through line 18 and is conducted through line 18 to the second stripping still 31. The naphtha distillate from the stripping still 31 is removed through line 32 and recycled through this line to the naphtha feed line 17 for reuse in the second extractor 15 of the process. The residue from the second stripping still 31, comprising a mixture of aromatic hydrocarbons, is removed through line 33 and can then be conducted to a suitable apparatus for recovery of the constituents of the mixture.

Example I

Coal hydrogenation neutral light oil having a nominal boiling point range of 100° to 260° C. and containing about one percent by weight of indoles and about one percent by weight of phenolic compounds was extracted first with ethylene carbonate solvent at a solvent to feed ratio of two to one in a 12-stage, 2 inch inside diameter York Scheibel extraction column. The ethylene carbonate extract containing indoles, phenols and aromatic hydrocarbons was back-extracted with heptane at a heptane to feed ratio to one to one in order to remove the bulk of the aromatic hydrocarbons in the extract.

The indoles, phenols and residual aromatic hydrocarbons were removed from admixture with ethylene carbonate in the residue from the heptane extraction by extracting them with isopropyl ether at an ether to feed ratio of one to one. This extract was then distilled to remove the isopropyl ether and was extracted first with water to remove the residual ethylene carbonate which dissolved in the ether and then with sodium hydroxide to remove the phenols. The final product after the sodium hydroxide extraction was a mixture of aromatic hydrocarbons containing about 12 percent by weight of indoles.

Example II

Coal hydrogenation neutral light oil having a nominal boiling point range of 100° to 260° C. and containing about one percent by weight of indoles and about one percent by weight of phenolic compounds was extracted first with ethylene carbonate solvent at a solvent to feed ratio which varied between one and 2.5 to one, using a 12-stage, 2-inch inside diameter York Scheibel extraction column. The ethylene carbonate extract containing indoles, phenols and aromatic hydrocarbons was back-extracted with n-heptane at a heptane to feed ratio of two to one.

The indoles, phenols and residual aromatic hydrocarbons were removed from admixture with ethylene carbonate in the residue from the n-heptane extraction by extracting them with isopropyl ether at an ether to feed

tract; distilling said ether from said third extract; washing said third extract with water to remove residual carbonate; washing said third extract with aqueous caustic to remove phenols; and washing said third extract with an aqueous mineral acid to remove nitrogen bases and leave as product said concentrated solution of indoles in aromatic hydrocarbons.
